PIPE GROOVING TOOL

John H. Krooss, New York, N. Y., assignor to
 Victaulic Company of America, New York, N. Y.,
 a corporation of New Jersey

Application June 26, 1947, Serial No. 757,091

3 Claims. (Cl. 82—4)

1

This invention relates to a pipe working tool and more particularly to a tool for cutting grooves in the periphery of pipes and the like.

In the past the grooving of the periphery of pipes near their ends, which are to be joined, has been accomplished in an inefficient way and in a way found largely impractical in the field by the adaptation of tools known as "portable square end pipe cutters." Differing in operating and design principles, these tools are difficult to operate, extremely inaccurate, and require unusual ingenuity to achieve their purpose.

It is an object of this invention to provide a tool for grooving pipe which is automatic, simple, easily operated and accurate in function in addition to being light in weight.

A further object of this invention is to provide a pipe grooving tool adaptable to operate on various sizes of pipe, it being readily changed from one size to another.

Another object of this invention is to provide a tool in which the cutter is kept under constant load or pressure during the grooving operation thereby rendering it self-feeding.

A still further object of the invention is to provide a grooving tool in which the depth of the groove cut is automatically controlled and which depth can be varied by simple adjustment of the cutter.

Another object of the invention is to provide a grooving tool having means to prevent longitudinal movement along the pipe, it being essential for satisfactory operation of the tool that no longitudinal movement occurs during the first few revolutions of the tool, or until the cutter or knife has cut a groove sufficiently deep to restrain any such movement.

A still further object is to provide means for locating the tool on the pipe end thus automatically locating the distance of the groove from the pipe end.

Further objects and advantages will be apparent from the following detailed description of the invention in connection with the accompanying drawings, in which:

Figure 1 is a top plan view of the grooving tool;

Figure 2 is a section on line 2—2 of Figure 1;

Figure 3 is a side elevation of the tool complete;

Figure 4 is a plan view of a conventional ratchet with handle used for rotating the grooving tool of the present invention;

Figure 5 is a view in elevation of the main body member free of the various assembly parts;

2

Figure 6 is a section on line 6—6 of Figure 5, showing the machined, tapped, and drilled portions of the main body member for receiving and supporting the various assembly parts;

5 Figure 7 is a view in side elevation of the cover member;

Figure 8 is a view of the cover member at right angles to that of Figure 7;

Figures 9 and 10 show modifications of the 10 invention.

Referring to the drawings more particularly, 1 represents the main body member as shown in Figures 2, 5 and 6. This is a single casting comprising the assembly base for all parts in 15 the mechanism. This body member has a bore 2 of an inside diameter to permit free action on a pipe end without unnecessary looseness. Cast on one end of the body member 1 around the periphery thereof are the notches 3 to engage 20 the dog 4 of the conventional ratchet 5 shown in Figure 4, and shown associated in position on the body member 1 in Figure 2. This is a more or less conventional ratchet consisting of a casting 5, Figure 4, bored out and tapped to receive 25 a handle 6 of standard pipe and bored and machined to receive a spring loaded ratchet pin or dog 4, which engages in the notches 3 on the periphery of the main body member 1. The ratchet pin 4 can be withdrawn by pulling on 30 the knob 4' against the action of the spring to permit removal of the ratchet from the main tool member 1.

The other end of the main body member 1, that is the end opposite that just mentioned 35 above, is machined, drilled and tapped in various locations, as best shown in Figure 6, for reception of the assembly parts. Referring to Figures 1, 2 and 3, it will be seen that supported in this end of the main body member are the 40 various assembly parts consisting of a pair of rollers 7 mounted on pins 8. The ends 9 of the pins 8 are supported in drilled openings 10 in the main body casting 1 as shown best in Figure 2. The other end 11 of the pins 8 upon which 45 the rollers are mounted are supported in a cover member 12 which will be described in detail later. In one side of the body member 1, substantially opposite the rollers 7, is an adjustable clamp screw 13 adapted to operate in a radial direction within the threaded opening 14 provided in the main body member 1. The rollers 7 and the clamp screw 13 constitute the means 50 for centering the pipe tool on the pipe initially, the clamp screw 13 being set up until the pipe 55 bears lightly against the two opposing rollers.

Once the cutting operation has commenced, it is found that this clamp screw 13 takes little or no thrust and, therefore, creates a minimum of friction. The end 13a of the clamp screw 13 is hardened to eliminate wear and the knurled handle or head 15 of the screw 13 permits easy adjustment.

The main body member 1 is provided with opposing machined grooves 16, 16 to receive a cutter 17 for grooving the pipe, said cutter 17 being adapted to travel in said grooves 16 in a radial direction.

The cover member 12 is secured to the main body member 1 by means of screws 18 and serves to tie the assembly into the body 1. The cover member 12 is provided with a radially outwardly extending portion 19 having a downwardly projecting shoulder 20. The downwardly projecting shoulder 20 has an opening 21 in line radially with the cutter 17. The opening 21 is adapted to receive a spindle 22 threaded at one end and having a handle 23 threadedly engaging the end of the spindle 22 to provide for adjustment of said spindle. The inner end of the spindle 22 has a U-shaped portion 24 adapted to receive the end 25 of the cutter opposite its cutting edge 26. A spring 21 is mounted on the spindle 22 and bears at one end against shoulder 28 of the U-shaped portion 24 of the spindle 22, and at the other end against the downwardly projecting shoulder 20 on the cover member 12. This spring constantly maintains pressure on the cutter during the grooving operation.

Mounted upon the upper side of the cover member 12 in line with the spindle 22 and travel of the cutter 17 is a stop member consisting of a short piece of bar stock 29 slotted as at 30 to receive a pin 31. The bar 29 is adjustably secured in position on the cover member 12 by means of a screw 32. The pin 31 is machined with a collar 33 to one side of its center point lengthwise. The longer end 34 of the pin 31 connects the cutter 17 to the U-shaped portion 24 of the spindle 22. The shorter end 35 of the pin 31 travels in the slot 30 of the bar 29. The collar 33 of the pin 31 prevents end movement of the pin in either direction.

The outer end 36 of the bar 29 is drilled and threaded to receive an adjusting screw 37 having its head 38 partially sunk in a groove 39 in the cover member 12 so as to anchor the screw 37 with respect to the cover 12 as far as longitudinal movement is concerned. It will be seen that by loosening the screw 32 and rotating the screw 37, the position of the slotted bar 29 can be changed in a radial direction thereby varying the limit of travel of the end 35 of the pin 31 and as a result automatically providing a control of the depth of travel of the cutter radially inwardly. Therefore by this simple adjustment feature a definite and accurate depth of the groove obtained by the cutter can be automatically controlled.

A stop consisting of a short bar 40 secured to the cover member 12 and projecting radially inwardly provides means for locating the tool on a pipe end thus automatically locating the distance of the cutter 17 from the end of the pipe and as a result the position of the groove cut with respect the end of said pipe.

The operation of the grooving tool thus far described is as follows:

The grooving tool is thrust on the end of the pipe to be grooved until the end of the pipe takes

up against the pipe stop 40 thus automatically locating the distance of the cutter 17 from the end of the pipe assuring the correct position of the cutter with respect to the end of the pipe.

5 Light hand pressure holds the tool in this position while the tool is centered on the pipe by adjustment of the clamp screw 13. Spring load compression is then placed on the cutter 17 by backing off the handle 23. With the cutter 10 17 now bearing on the outer surface of the pipe at the proper position, the tool is now ready to begin cutting the groove. Cranking action is then started by up and down strokes of the ratchet handle 6. The tension of the spring 27 is sufficient to feed the cutter 17 until the travel of the cutter 17 is stopped by reason of the end 35 of the pin 31 reaching the end of its travel in the slot 30 of the bar 29. At this point the cutter removes any burrs left in the groove and the 15 release of the cutting load indicates to the operator that the groove is complete, whereupon the cutter 17 is then withdrawn against the spring 27 by turning up on the handle 23. The 20 grooving tool is then withdrawn from the end 25 of the pipe and is ready for the next operation.

Figures 9 and 10, show a modification of the pipe grooving tool. In this modification all the various parts of the tool assembly are the same as above set forth with one exception which will 30 now be described.

For satisfactory operation of the tool it is essential that no longitudinal movement occurs during the first few revolutions of the tool, or until the cutting knife has cut a groove sufficiently deep to restrain any such movement. If the 35 axes of the tool rollers 7 are exactly parallel with the axis of the pipe there is no tendency for the tool to move in either direction longitudinally on the pipe. However, the force applied to the 40 ratchet handle in rotating the tool, the uneven surface of the pipe being grooved, and the necessary play in the roller assembly do cause a tendency for the tool to move along the pipe. The longitudinal movement in one direction is limited 45 by the pipe stop 40. In the other direction nothing prevents the tool from creeping off the pipe.

In order to counteract creeping of the tool in a direction off the pipe and to provide a positive creep in the other direction, the modification 50 as shown in Figures 9 and 10 is provided.

In this modification the rollers 7' in the tool are set with their axes *aa* at a slight angle to the pipe axis *bb*. That is, the rollers 7' are mounted in the grooving tool so that the front end of the 55 roller axis *aa* is inclined in the direction in which the tool revolves or moves.

In Figures 9 and 10 assume the pipe *x* is stationary and the tool is revolving about the pipe in a clock-wise direction as shown by the arrows. The front end of the roller axis *aa* leads the rear end by a slight amount in the clockwise direction. As the tool revolves about the pipe the rollers 7' also revolve and tend to move the tool further 60 on to the pipe *x* until the longitudinal movement is prevented by the pipe stop 40. When this condition is reached, rolling and sliding contact occurs between the rollers and the pipe. As a result throughout the entire grooving operation a positive force is exerted by the rollers 7' holding it onto the pipe *x*.

From the foregoing it is believed the construction, operation and advantages of the tool may be readily understood and it will be manifest that changes may be made in the details of the

device without departing from the spirit of the invention, as expressed in the following claims.

What is claimed is:

1. In a pipe grooving tool, a housing formed with an opening therein for receiving a pipe, 5 ratchet means mounted on said housing for rotating said housing with respect to a pipe seated in said opening, rollers carried by said housing bordering said opening for engaging a pipe received in said opening, and mounting means 10 mounting said rollers obliquely with respect to the axis of said opening whereby on the rotating of said housing, with respect to a pipe received therein, said housing will tend to travel along the pipe, an abutment member for engaging the end of a pipe and limiting the travel of the housing therealong, a cutting tool mounted on said housing for radial movement toward and away from the axis of said pipe receiving opening, resilient means for feeding said cutting tool in operative direction, positive means engaged with said cutting tool for retracting the same against the action of said resilient means, a stop pin extending laterally with respect to said cutting tool, a stop member mounted on said housing in overlapping relation with respect to said stop pin, and an adjusting member engaged with said housing and said stop member for setting said stop member at desired position to limit the inward movement of said cutting tool in response 30 to the action of said resilient means.

2. In a pipe grooving tool, a housing formed with an opening therein for receiving a pipe, means on said housing for rotating the same with respect to a pipe seated in said opening, an abutment member carried by said housing and extending into the path through said opening for engaging the end of a pipe seated in said opening, rollers carried by said housing and bordering said opening for engaging a pipe received in 35 said opening, mounting means for the rotatable mounting of said rollers on said housing, said mounting means including means for mounting said rollers obliquely with respect to the axis of said opening whereby, on the rotation of said housing with respect to a pipe received within 40

said opening, said housing will tend to move inward along the pipe and thus maintain itself in desired position thereon by maintaining said abutment member against the end of the pipe, and a cutting tool mounted on said housing to project into said opening and for movement with- in the same.

3. In a pipe grooving tool, a housing formed with a portion for the axial reception of a pipe to be grooved, means carried by said housing for rotating the same about a pipe seated within said receiving portion, a pipe end engaging stop carried by said housing for engaging a pipe received within said pipe receiving portion for initially mounting said housing in desired axial position on a pipe, a plurality of rollers, mounting means for the rotatable mounting of said rollers on said housing in position to engage a pipe received within said pipe receiving portion, said mounting means including means for mounting said rollers obliquely with respect to the axis of said pipe receiving portion, whereby said housing when rotated will tend to move inward on said pipe and keep itself in desired position by maintaining said stop against the end of the pipe, and grooving means mounted on said housing and extending inwardly of said receiving portion for engaging a pipe received therewithin.

JOHN H. KROOSS.
